CLAIM

The ornamental design for a merry-go-round, substantially as shown and described.

DESCRIPTION

FIG. 1 is a perspective view of a merry-go-round showing my new design;

FIG. 2 is a fragmentary side elevational view of the axial portion thereof with the remaining portions of my design omitted for ease of illustration;

FIG. 3 is a top plan view thereof; and

FIG. 4 is a side elevational view thereof.

FIG. 1

FIG. 2

FIG. 3

FIG. 4
